COAL MINING MACHINE

Robert Johnson, Lafayette, Colo., assignor of one-fourth to Robert M. Johnson, Cheyenne, Wyo.

Application January 5, 1945, Serial No. 571,519

9 Claims. (Cl. 262—12)

This invention relates generally to mining machines and, more particularly, to improvements in machines operating under fluid pressure for breaking down sections of a coal seam.

A principal object of the present invention is to provide a machine or apparatus of the character stated made up of a plurality of hydraulically operated pressure or power units operatively coupled together and constructed in a novel manner whereby the applied pressure against opposing faces of the cut in which the apparatus is located will progress from one power unit to the next so that the section to be broken out will be broken in pieces instead of as a solid block.

Another object of the invention is to provide a pressure applying apparatus of the character stated made up of the series of operatively connected hydraulic pressure units, wherein each unit is provided with a fluid pressure shut-off valve between the supply port for the unit and a movable feet or ram whereby when such foot or ram has been extended to its extreme position such valve will be closed and the pressure will be automatically taken off of the foot and passed on to the next unit.

Still another object of the invention is to provide a coal breaking apparatus of the character stated in which the ram feet are connected with the body of the ram by heavy rubber strands which effect the return of the feet to starting position when the fluid pressure is relaxed.

Still another object of the invention is to provide in a coal breaking apparatus of the character stated, a plurality of operatively connected, hydraulically actuated power units or rams wherein the rams are of progressively increasing internal size so that they will be actuated progressively to break out the seam block or section of coal, in pieces rather than in a solid block.

Other objects and advantages of the invention will become apparent as the description of the same proceeds and the invention will be best understood from a consideration of the following detailed description taken in connection with the accompanying drawings forming a part of the specification, it being understood, however, that the invention is not confined to a strict conformity with the showing of the drawings but may be changed or modified so long as such changes or modifications mark no material departure from the salient features of the invention as expressed in the appended claims.

In the drawings:

Figure 1 is a sectional view through a portion

of a coal seam showing the application of the present invention in breaking away a section of such seam.

Figure 2 is a view in side elevation, with parts broken away, of one of the pressure or power units.

Figure 3 is a view partly in vertical section and partly in front elevation of one of the units showing, in longitudinal section, the ends of two coupling links connected therewith.

Figure 4 is a sectional view on the line 4—4 of Figure 3.

Figure 5 is a detail sectional view, on an enlarged scale of a portion of the valve mechanism.

Referring now more particularly to the drawings, the numeral 10 designates an undercut such as is commonly formed in a coal seam to set off a block or section of coal, designated 11, which is broken away from the main body of the seam, to be hauled out. Such undercuts are usually extended for a distance of from five and a half to nine feet and are approximately six inches high.

The machine of the present invention is made up of a series of operatively coupled pressure applying or ram devices, each of which is generally designated R and the number of such devices making up the completed machine will vary according to the depth of the undercut. An undercut of a depth of seven feet is most commonly used and for such a depth a machine made up of three of the ram units would be employed. For a greater depth such, for example, as a nine foot cut, the machine would be made up of four of such units.

The several rams making up the complete machine are of identical construction, the single exception being that the fluid pressure chambers within the rams will be of different sizes and the units will be assembled so that the unit nearest the outer part of the undercut or nearest the pressure machine supplying fluid to the units, will be of maximum interior size and the succeeding ones will be progressively smaller so that the outer unit will operate ahead of the inner unit and will develop more power than the succeeding unit and such units will function progressively inwardly according to the sizes of the fluid pressure chambers thereof. It will thus be seen that with this setup the greatest pressure or power will be applied to the coal body 11 near the outer side of the undercut and such body will be broken off in stages by the different units as the power passes from one to the other.

Since the construction of the several units is

the same, except for the one feature stated, the description of one unit will apply to all and therefore such a description will be confined to a single unit.

The ram unit comprises a long top or head portion 12 which is transversely rounded or arcuate and which at each end has the wing extension 13 which is formed at opposite sides in the depending spaced ears 14.

Formed integral with the head 12 at the center thereof, is the piston body 15, the free end of which is formed to provide an interiorly threaded recess 16 which communicates at its inner end with the chamber 17 and which chamber in turn is in communication with the bore 18 which extends outwardly into the head of the ram unit and joins the longitudinal fluid conducting passage 19 which at each of its ends is threaded as indicated at 20, to facilitate the connection therewith of an end of a fluid conducting hose 21.

Telescopically nested upon the piston 15 are the piston sleeves 22 and 23. The sleeve 22 is immediately adjacent to the piston 15 while the sleeve 23 is upon the outer side of the sleeve 22 as shown.

The sleeve 22 is of an inside diameter through the major part thereof, greater than the diameter of the piston 15 and adjacent to the inner end of this sleeve there is formed the annular shoulder 24 which is of a diameter to closely encircle the piston thereby dividing the space between the wall of the piston and the inside wall of the sleeve into a packing gland chamber 25 and an extent of movement determining space 26.

At its outer end the inner piston sleeve 22 is formed to provide the encircling outwardly extending stop flange 27.

The outer piston sleeve 23 is formed somewhat similarly to the sleeve 22 in that it is provided with the interior annular shoulder 28 which divides the inside of the cylinder into the packing gland chamber 29 and the extent of movement determining space 30.

Upon its outer end, however, the sleeve 23, instead of having an encircling flange, is of slightly reduced diameter and is threaded as indicated at 30, for the threaded application thereto of the foot member 31 which closes the outer end of the outer sleeve 23 as shown.

The interior of each sleeve at its inner end is threaded as indicated at 32, to receive a packing gland ring nut 33 which maintains in position against the adjacent shoulder, the packing material 34. Such material for the inner sleeve is compressed into the wall of the piston 15 while the material for the outer sleeve is pressed against the outer side surface of the inner sleeve 22 thus preventing fluid leakage between the moving parts.

As shown the inward telescoping movement of the sleeves is limited by the abutment of the inner ends of the sleeves against the underside of the head 12 and the outward movement of the outer sleeve 23, together with the foot 31, is limited by the engagement of the shoulder 28 against the stop flange 27 which is carried at the outer end of the inner sleeve.

The outward movement of the inner sleeve 22 upon the piston body 15 is limited by the engagement of the shoulder 24 against the rim 35 of a valve retaining plug 36 which is threaded into the recess 16.

The plug 36 is centrally chambered as indicated at 37 and this chamber leads outwardly

through the head of the plug by way of the passage 38 into the fluid chamber 39 which is formed between the domed inside wall of the foot 31 and the flat head of the plug and the adjacent end of the inside sleeve 22 and flange 27.

Seated within the plug chamber 37 is an expansion spring 40 and extending through this spring is the stem portion 41 of a plug valve 42, the rounded underside 43 of which is designed to contact the annular seat 44 formed around the inner end of the plug chamber 37, when the valve is shifted outwardly against the resisting tension of the spring 40. As shown this spring maintains the valve unseated so that fluid passing through the passage 18 will flow around the valve stem through the chamber 37 and the passage 38 into the fluid chamber 39.

The outer end of the valve stem 41 has connected therewith one end of a chain 45 while the opposite end of such chain is attached, as indicated at 46, to the foot 31. This chain is of the proper length to permit the nearly full extension of the sleeves outwardly on the piston and just prior to the completion of such full outward movement of the sleeves the valve 42 will be pulled firmly onto the seat 44 so as to shut off the further flow of fluid through the passage 18.

After the chamber 37 and passage 38 have been closed by the valve 42 the full pressure of the fluid will be carried over to the next ram unit while the unit in which the valve has been closed will be maintained in extended or expanded condition until the fluid pressure has been relaxed.

The foot portion 31 of each unit has the opposite radial extensions 47 each of which carries a pair of spaced upstanding ears 48 which are provided with the outwardly opening slots or notches 49. Each pair of ears 48 is disposed beneath a pair of ears 14.

Extending across between and connecting each pair of ears 14 is a pin 50 and a corresponding pin 51 connects each pair of ears 48 by having its ends engaged in the notches 49 as illustrated. The pins 51 are preferably headed as shown so as to prevent them from moving axially and slipping out of the notches 49.

Each adjacent pair of pins 50 and 51 passes through and are coupled together by the heavy elastic band 52, the width of which is substantially equal to the distance between the ears of each pair. These bands, located upon opposite sides of the unit, tend constantly to pull the foot member 31 inwardly so as to shift the piston sleeves into nested relation upon the piston. When the fluid is introduced into the unit and the piston sleeves and the foot are moved outwardly the bands are placed under tension and by reacting, after the fluid pressure is relaxed, they pull the sleeves back to starting position as described.

The units of the machine are connected in a continuous fluid conduit by means of the pipe or tube sections 21 which are flexible but are of sufficient strength to withstand high fluid pressure. In addition to these pipe sections or tubes 21, the units are connected by the rigid links or link bars 53. These links are hollow and are of substantially U-shaped cross section. Each end of each link bar is disposed between a pair of ears 14 and pivot pins or screws 54 are extended through the sides of the links and into the adjacent ears 14 so that the link bar will be coupled with the unit.

As illustrated the open sides of the link bars are directed downwardly. By this means ample protection is given to the tubes 21 which extend lengthwise of the links within the same, while at the same time the tubes and the links may be easily and quickly separated or a link may be taken out from between two units, without causing any difficulty in separating the link from the tube which it shields.

The pivot pins 54 extend perpendicular to the axis of the piston and the piston sleeves. Thus it will be seen that as the body of coal is broken away by the units which are expanded successively, the unit lying beneath the portion of the coal body which has been broken out, may drop or swing downwardly without danger of damaging the connection between itself and the next unit, or damaging the hose which carries the fluid under pressure from one unit to the other.

From the foregoing it will be seen that there is provided in the machine herein described, a novel arrangement whereby the coal body may be broken down in portions or sections, by the several pressure applying units or rams due primarily to the connection together of rams of successively decreasing sizes or power. It will also be apparent that by reason of the novel interior construction of each ram, as soon as the ram foot has been moved outwardly to the maximum from the head, the application of further power to the foot is shut off so that the full force of the fluid can be carried over to the next ram. In this manner the application of the power to the rams is progressive to further insure the breaking down of the coal body in sections as described.

While in the illustration of the present invention and the description thereof the use of the invention has been confined to coal breaking, it is to be understood that the device may be used for other breaking operations and that there is no intention of limiting the invention to the coal mining art.

I claim:

1. A mining machine of the character stated, comprising a plurality of fluid actuated ram units, means connecting said units together in articulated relation, means for conducting fluid under pressure from one unit to the other, and means for successively shutting off the supply of operating fluid to the units as the units are each operated to a predetermined extent.

2. A mining machine, comprising a series of fluid actuated ram units arranged in spaced relation to form a line, rigid coupling link bars interposed between the units and pivotally attached at their ends to the units for pivotal movement relative to the units on axes extending perpendicular to the direction of thrust of the units, means for conducting fluid under pressure from one unit to the other, and means for automatically shutting off the application of fluid pressure successively to the units through the series from one end to the other.

3. In a mining machine of the character stated, a fluid pressure operated ram, comprising a piston body having a head, a foot member, telescoping piston sleeves slidably supported upon said piston, said foot being coupled with the outer one of the telescoping sleeves, said foot having a wall in opposed relation to and spaced from the end of the piston and of a sleeve to form a pressure chamber, means for introducing fluid through the piston into the pressure chamber to effect axial extension of the sleeves upon the piston, said foot and head members each carrying two pair of op-

positely positioned ears, the ears of one member being in cooperative relation with the ears of the adjacent member, pin members connecting together the ears of each pair, and flexible bands connecting the pins of the ears of the head member with the pins of the adjacent ears of the foot member and constantly urging movement of the sleeves together on the piston.

4. A mining machine ram unit of the character set forth in claim 3, with means for effecting the interruption of the flow of the fluid to said fluid chamber when the foot member has moved outwardly to a predetermined extent away from the head member.

5. A mining machine ram unit of the character stated in claim 3, with means for effecting the shutting off of the flow of fluid to said fluid chamber, and means operated by the foot member upon movement of such member outwardly to a predetermined position with respect to the head member for moving said shutting off means to operative position.

6. In a mining machine of the character stated, a fluid actuated ram unit comprising a head member, a piston body integral with said head member, a pair of telescopically assembled sleeves, the inner one of the sleeves being slidably mounted upon the piston and the outer one of the sleeves being slidably mounted upon the innermost sleeve, a foot member carried upon the outer end of the outermost sleeve and having an inner wall curved outwardly away from the adjacent end of the piston and the innermost sleeve to form a fluid pressure chamber, packing glands carried by the sleeves at the inner ends thereof and upon their inner sides, one of the glands engaging the wall of the piston and the other gland engaging the outer wall of the innermost sleeve, means for limiting the outward movement of the sleeves on the piston and with respect one to the other, a fluid conduit formed through said head and having a lateral branch leading through the piston to said pressure chamber, a valve means in said lateral branch and normally positioned to permit the flow of fluid therethrough to the chamber, and means for effecting the automatic closing of the valve means upon the movement of the foot member to a predetermined extent outwardly from the head member.

50 7. A mining machine ram unit of the character stated in claim 6, in which said valve means includes a valve seat encircling said branch of the conduit, a plug valve element movable axially of said conduit branch, spring means normally maintaining the valve element raised from the seat, and a flexible coupling between the valve element and the foot member, said flexible coupling being of a length to be drawn taut and to effect the movement of the valve member onto its seat when the foot member has moved outwardly to the said predetermined position from the head member.

60 8. In a mining machine of the character stated, a fluid operated jack unit comprising a head member, a piston body integral with the head member, a pressure foot supported upon the piston body for movement axially thereof relative to that end of the piston body remote from the head, a fluid conducting passage formed in the head and axially through the piston body, the said passage discharging from the end of the piston body toward the pressure foot for effecting axial movement of the pressure foot relative to the piston body upon the discharge of fluid under pressure therefrom, a normally open valve within the pas-

65 70 75

sage, and means for effecting the closing of the valve to shut off the flow of fluid through the passage toward the pressure foot, when the pressure foot has moved a predetermined distance axially of the piston body away from the adjacent end of such body.

9. A pressure jack unit of the character stated

in claim 8, with elastic members coupling the pressure foot with the head member and constantly urging movement of the pressure foot axially of the piston body in opposition to the action of the pressure fluid.

ROBERT JOHNSON.
